UNITED STATES PATENT OFFICE.

WILLIAM J. WILKINSON, OF BALTIMORE, MARYLAND, ASSIGNOR OF ONE-FOURTH TO WILLIAM B. USILTON, OF CHESTERTOWN, MARYLAND, AND ONE-FOURTH TO LLOYD WILKINSON, OF BALTIMORE, MARYLAND.

VOTING-MACHINE.

SPECIFICATION forming part of Letters Patent No. 792,373, dated June 13, 1905.

Application filed August 15, 1904. Serial No. 220,691.

To all whom it may concern:

Be it known that I, WILLIAM J. WILKINSON, a citizen of the United States, residing at Baltimore, in the State of Maryland, have 5 invented certain new and useful Improvements in Voting-Machines, of which the following is a specification.

This invention relates to improvements in voting-machines, and has among its objects 10 the provision of a simple machine by which the ballots commonly used and often of a complicated nature may be entirely dispensed with, the liability of the voter making errors and his vote thrown out overcome, and the 15 labor of ascertaining the total votes cast for each candidate accurately determined at a glance.

By means of the invention contentions between the election officials of the opposing 20 parties as to the counting or throwing out of ballots is entirely overcome and the final results of the election quickly reached.

With these and other objects in view the accompanying drawings illustrate one form 25 of device for carrying the invention into practical effect, in which—

Figure 1 illustrates a top plan view of the machine; Fig. 2, a front elevation of the same, the cover being swung open to reveal the tabulating devices. Fig. 3 illustrates an end elevation of the machine. Fig. 4 shows a 30 rear perspective view of the same. Fig. 5 illustrates a perspective plan view of a portion of the device to mechanically determine 35 the number of candidates to be voted for by a single voter. Fig. 6 shows an enlarged sectional detail of the tabulating mechanism. Fig. 7 illustrates a detail perspective view of 40 a device to prevent more than one movement or operation of the tabulating device by one person. Fig. 8 is a view of the same with the lower end of the rod in the normal inoperative position. Fig. 9 shows one form of 45 key device for operating the rods.

Referring to the drawings by numerals, 1 designates a casing of any suitable size and in the present instance having a horizontal bed or top 2, a bottom 3, parallel with said top, 50 and a wall or screen 4, projecting from said top and serving to shield the actions of the 50 voter. The case is also provided with a door 5, which during the progress of voting covers the tabulating or registering mechanism and prevents inspection of same.

The bed or top 2 (see Figs. 1 and 5) is provided with a vertical slot 6, which extends in a longitudinal direction. At one side of the slot the bed or top is provided with a plurality of parallel spaces 7, which are preferably printed on a sheet and secured to the top, 60 and each of said spaces is designed to contain the name of a candidate. It will be noted by reference to Fig. 1 that the spaces in the present instance are arranged in sets or sections 8, 9, and 10. The object of thus separating the spaces into sections is for the purpose of placing all the candidates of the opposing parties who are running for the same office in one section. For example, in section 8 there are five spaces, each of which is to 65 contain the name of one of the candidates. Thus there are five candidates, all running for the same office. In section 9 there are eight spaces, and consequently eight candidates, all running for another office, and in 70 section 10 there are sixteen candidates, and consequently sixteen spaces, one for the name of each candidate for still a different office. It is obvious that the particular form and number of spaces or sections is entirely 75 immaterial and will be varied to suit the particular election being held. On the opposite side of the slot 6 the bed or top 2 is further provided with a plurality of holes 11, which extend vertically through the top, and these 80 holes are arranged so that each has position directly in line with one of the spaces 7 on the opposite side of the slot.

Within the case and below the top or bed are a plurality of parallel vertical rods 12, 90 which extend from the bottom 3 up to the bed or top 2. At the lower end each rod is seated in a socket or depression 13 in the bottom of the case, and the upper end of each rod projects from the under side of the bed or top 2 95 and terminates in the hole 11 directly over it.

and which serves as a bearing to sustain the rod in a vertical position. The extreme upper end of each rod is also provided with a squared head 14, which when the rod is in the 5 normal or inoperated position is wholly within the hole 11 and beneath the top surface of the bed or top 2.

Beneath the bed or top 2 and extending in a direction parallel with the slot 6 is a slide or 10 rod 15, one end 16 of which projects through an end wall of the case and in the present instance is provided with an inverted-U-shaped plate 17, which will presently be described. This slide or rod 15 has position so that one 15 side 18 will register with the vertical wall of the slot 6, and said slide 15 is provided with laterally-projecting pins 19, which are arranged on the slide so as to have a position beneath the top, but directly below the division-lines 20 between the sections 8 and 9 and 20 9 and 10. A plurality of plates 21 are also provided on the bed, and these plates each have a downturned flange 22, which enters the slot 6 and projects downwardly and adjacent the side 18 of the slide. It will be 25 noted that these plates are of the same width as the spaces 7 and by sliding horizontally may be made to entirely cover any one of the holes 11 and also the head of the rod in said 30 hole. This feature is advantageous and will presently be fully explained. By reference to Fig. 5 it will be seen that the downturned flanges 22 of the plates 21 have position between the pins 19 on the slide 15, and by reference to Fig. 1 it will be noted that the number of plates adjacent each section is less than the total spaces of said section. It will also be understood that the plates adjacent one section are separated from the plates of the 35 40 next adjoining section by the pins 19 on the slide 15, so that while the plates are movable in a direction parallel with the slot 6 their movement is limited by the pins, and the plates of one section cannot be moved into 45 the adjoining section. The number of plates for each section is determined by the number of candidates running for the office that section represents and the number of persons to be elected to fill that office. For example, in 50 section 8 there are five candidates, from which three are to be elected. Therefore the number of plates required for that section will be two, which, it will be seen, is the difference between the number of candidates and the 55 number to be elected. Again, in section 10 there are sixteen candidates; but only eight of that number are to be elected and eight plates are there required. It will be understood that the number of plates for each section must be such as will only leave uncovered a number of holes 11 equal to the number of persons to be elected. As an example of this in section 8 there are five candidates, only three of whom are to be elected. Therefore 60 65 70 two plates must be provided, which may be

shifted so as to register with the spaces containing the names of the two candidates the voter has decided not to vote for. By thus shifting these two plates the holes 11 opposite the names of said two candidates and the 70 head ends of the rods in said holes will be covered by the plates. By means of a suitable key 23 the uncovered head ends of the rods may then be operated to record the vote for the desired candidate through mechanism 75 now to be described.

The rods 12 are provided with screw-threads 24, on which a head 25 of any suitable form is sustained. In practice these threads are cut on the rods ten to the inch 80 for a purpose to be presently set forth. This head in the present instance has the form of a nut and at one side is provided with a laterally-projecting pin 26, as clearly seen in Fig. 6, which projects through a vertical slot 27 85 in a vertical partition 28 at the rear of the rods. This partition is provided with a plurality of said slots 27, which are so disposed that each slot will have position directly behind one of the rods, so as to receive the pin 90 of the head carried on said rod. The outer vertical surface of the partition 28 is provided with a series of parallel horizontal lines 29, a few of which are shown in Fig. 2, and these lines form a scale adjacent the 95 traveling heads 25, by which the position of the head on the rod will indicate the total votes registered for the candidate whose name appears on the bed or top opposite the upper end of the rod. These scale-lines are 100 placed one-tenth of an inch apart, so that each revolution of the rod will cause the head 25 to travel successively from one line to another. It will be understood that the pin 26 on each head 25 by projecting through the 105 vertical slot 27 prevents the turning of the head when the rod is turned, and as the rod is turned by the key the head is caused to advance on the rod a distance equal to the space between each two adjoining scale-lines 110 on the partition. The particular location of the partition and the scale-lines are immaterial, and they may be placed in front of the rods as readily as behind them and an unobstructed view of the scale thereby obtained. 115

The lower ends of the rods 12, as have been explained, are each seated in a socket 13 in the bottom of the case, and their upper ends merely fit loosely in the holes 11 in the bed 120 or top 2. By thus sustaining the rods they are capable of vertical movement, and this movement is utilized to positively prevent the voter from recording more than a single vote for any one candidate or voting for 125 more candidates than he is entitled. The mechanism by which this is accomplished will now be described.

Adjacent each of the sockets 13 in the bottom of the case is a cam-surface 30, as clearly 130

shown in Figs. 6, 7, and 8, which in the present instance extends from the bottom upwardly and around the circumference of the lower end of the rod. The higher point of 5 the cam terminates in the present instance at the rear of said rod and forms a vertical stop 39. A pin 31 projects laterally from the lower end of the rod and when in the normal inoperated position rests on the lowermost 10 surface of said cam, as shown in Fig. 8. At the rear of the lower ends of the rods and within the case is a plate 32, which in the present instance rests on the bottom 3 with the front longitudinal edge 33 confronting the cam-surfaces 30. At the opposite longitudinal edge 34 of said plate are flat leaf-springs 35, which press against said edge and yieldingly press the plate forward toward the cam-surfaces. The front edge 33 of this plate is provided with a plurality of stop-plates 36, which latter in the present instance are of an angle-iron form. These stop-plates are positioned on the sliding plate so that each will have a position adjacent one of the cam-surfaces. 15 5 Each stop-plate is provided with a downwardly-curved corner 37, adjacent the elevated surface of the cam 30, and as each rod is turned in the socket 13 the pin 31 on said rod will ride up the inclined cam-surface and be delivered onto the stop-plate at the rear. This elevation of the pin over the cam-surface causes the rod to which it is rigidly attached to be elevated or raised in the socket and also causes the upper head end of said rod to be 20 projected through the hole 11 and above the bed or top 2, as seen at 38 in Fig. 2, and will prevent further movement of the plates 21 on the bed.

Above the sliding plate 32 and within the 25 case is a shaft 40, one end of which projects through the end wall and is provided with a hand-wheel 41. Projecting downwardly from this shaft are two arms 42, the lower ends of which fit into sockets or depressions 43 in the upper surface of the sliding plate 32. By turning the wheel 41 and shaft 40 the arms 42 will cause the plate 32 to be moved horizontally on the bottom against the action of the springs 35, and this movement of 30 said plate will withdraw the stop-plates 36 from beneath the pins 31 and permit the rods to drop back into their normal positions with the pins 31 adjacent the stop-wall 39 of the cams. When in this position, the stop-wall 35 serves to prevent the rotation of the rods in a direction that would cause the heads 25 to be returned toward their starting-point, and thus subtract from the votes previously cast. A bell or other signal 44 on the interior of the 40 box is connected to the shaft 40, and when the latter is rotated to release the rods and register the votes the bell is operated to give an audible signal that the vote has been registered. As soon as the shaft has been operated and the rods operated by the voter

returned to their normal positions, with their upper head ends beneath the top or bed, the vote has been entirely registered; but the plates 21 will be in the position as set by the voter, and the succeeding voter by merely 45 noting the position of the plates would have accurate knowledge of the vote previously cast. In order to remove such a fatal objection, provision has been made whereby the plates may be disturbed and all evidence 50 of the vote previously registered removed. It has heretofore been explained that the pins 19 on the slide or rod 15 project laterally beyond the flanges 21 at the ends of each series of plates. By this arrangement the 55 voter or one of the election officials may grasp the U-shaped plate 17 and partly withdraw the slide, and this movement of the slide will bring the pins 19 in contact with the flanges 21 of the plates and move the latter from their adjusted positions and collect them at the ends of their respective sections, and thereby prevent the next voter from 60 gaining a knowledge of the vote previously registered. 50

In practice the operation is as follows: The 65 qualifications of the voter having been passed on favorably by the usual officers, the voter is provided with the operating-key 23 and takes his position at the side of the machine. 70 He then slides the plates 21 over the bed or top 2, so as to move them out of register with the spaces 7, containing the names of those candidates for whom he desires to vote. As the difference between the number of 75 plates and the number of candidates equals the number of votes entitled to be registered, the removal of the plates to uncover the holes 11 opposite the names of the candidates to be voted for will cover the holes opposite the names of all the other candidates. 80 When the plates have all been arranged to suit the voter, the holes remaining uncovered will be opposite the names of the candidates for whom he proposes voting. The voter now 85 takes the key 23 and places it over the exposed head end 14 of one of the rods 12 and turns the rod. This turning of the rod causes the latter to be elevated by means of the pin 31 riding up on the cam 30, and the 90 head end 14 of the operated rod will project above the bed or top 2. The next uncovered rod will then be operated in the same manner and left projecting above the bed. When all the uncovered rods have been 95 operated, as seen in Fig. 2, the head ends of said rods will project at each side of the plates registering with the names of those candidates not voted for, and as the rods provided for these latter candidates are covered by 100 the plates and the plates cannot now be shifted the voter cannot intentionally or unintentionally vote for more candidates than he is entitled. It will also be seen that in operating the rods to register a vote the rods 105

can only be turned until their pins contact with the stop-plates 36, at which time the movement or rotation of the rods is brought to a stop. At this point the pins 31 will have 5 position on the stop-plate, but will have been rotated so as to pass beyond the vertical end 39 of the cam-surface. In turning, the rods will screw through and slightly raise the heads 25 thereon. When the voter has operated 10 the rods to register his vote, one of the election officials will turn the wheel 41 and through the mechanism heretofore described release and permit the rods to drop to their normal positions. As soon as this has been 15 done the voter, or one of the election officials, if preferred, will grasp the U-shaped plate 17 on the end of the rod 15 and by pulling said rod out and then returning it will disturb the position of the plates 21 on the bed, and 20 thereby remove all evidence as to how he voted. The next voter will then register his vote in the same manner. When the polls are closed and the time has arrived for tabulating the votes, the door or other covering 5 25 is removed to expose the scale 29, and by noting the position of the heads 25 with respect to said scale the total votes registered for each candidate will be ascertained, each line below the edge of the head representing 30 a vote cast for the candidate said head represents.

It is to be understood that many alterations and modifications of the parts may be made without departing from the spirit of the invention. It is also to be understood that it is immaterial as to the number of rods or registering devices employed, as a machine may have as many rods as there are candidates and may have one rod representing all the 35 candidates of a single party, so that the operation of one rod would register a vote for all the candidates of the party that rod designates.

Having thus fully described my invention, 40 what I claim as new, and desire to secure by Letters Patent, is—

1. In a voting-machine the combination with a plurality of registering devices movable in two planes, of means whereby the 45 movement of said devices in one plane will record a vote; selecting means primarily under the control of the voter for determining which registering devices he shall operate, and means whereby the movement of the selected registering devices in the other plane will prevent further movement of the selecting means.

2. In a voting-machine the combination with a plurality of registering devices, of movable devices to prevent access to a predetermined number of said registering devices, means whereby the movement of said registering devices in one plane to record a vote will simultaneously move them in another 55 plane to lock the movable devices.

3. In a voting-machine the combination with a plurality of rotatable registering devices, of means whereby the rotation of said devices will record a vote; means for moving said devices in a plane at right angles to that in which they rotate, and means coacting with said registering devices after they have been moved in said right-angle plane to determine the number of votes to be cast.

4. In a voting-machine the combination with the registering devices for each candidate, of devices to cover the registering devices of not-voted-for candidates to prevent their operation, said devices being adjustable by the voter; means to operate the registering mechanism in one plane to record a vote and in another plane to lock the cover devices, and means to positively disturb the adjustment of said cover devices to destroy the evidence of the vote.

5. In a voting-machine the combination with a case provided with registering mechanism for each candidate which are movable in two planes, of devices to be operated by the voter for determining the number of votes to be registered; means for operating the registering devices in one plane to record a vote; means for operating said registering devices in another plane to prevent further operation of the vote-determining devices and also to prevent their own operation.

6. In a voting-machine the combination with a case, of a plurality of rods sustained in said case and movable in two directions; means whereby the rotation of the rods will record the votes cast, and means for moving the rods in a lengthwise direction as they are rotated to prevent them from being operated more than once by any one voter.

7. In a voting-machine the combination with a case provided with a rod, of a plurality of rods in said case and normally below the surface of said bed; a plurality of movable devices also on said bed and arranged to cover a number of said rods, means for rotating the uncovered rods to register each vote, and means to project said rods beyond the surface of said bed to prevent further movement of the movable devices until after the voting operation is completed.

8. In a voting-machine the combination with a case provided with a bed having a plurality of bearings, of a plurality of rods in said case and each having an end in one of said bearings; a plurality of plates on said bed and movable over said bearings, means for rotating the rods to register the votes, means for projecting the rods between said plates to lock the latter against movement and means for positively disturbing the position of the plates to destroy the evidence of the vote.

9. In a voting-machine the combination with a case, of a plurality of rods in said case and provided with registering devices; plates movable across the ends of said rods to pre-

5 vent access to some of the latter; means whereby the rotation of each uncovered rod will record a vote; means for moving the rods in a lengthwise direction simultaneously with their rotation to project them above the bottom surface of said plates, and means to hold each operated rod projected until all the votes are recorded.

10. In a voting-machine the combination with a case, of registering devices in said case; adjustable devices for permitting access to a limited number of said registering devices, and a slide movable in a direction parallel with the movement of said adjustable devices to disturb the latter.

15. In a voting-machine the combination with a case, of a plurality of rods in said case; registering devices operated by said rods; plates on said case and projecting over the operating ends of a limited number of said rods, and a slide movable adjacent the ends of said rods and coacting with said plates to positively disturb the adjustment of the latter after each vote has been registered.

20. In a voting-machine the combination with a case provided at one side with a slot and also having a plurality of holes adjacent said slot; rods in said case and having their operating ends normally within said holes; 25 plates movably secured to said case and projecting over said holes; registering devices coacting with said rods, and a slide adjacent said slot and by means of the latter coacting with said plates to disturb the positions of the latter.

25. In a voting-machine the combination with a case provided at one side with a slot and a plurality of holes adjacent said slot; rods in said case and having their operating ends within said holes; plates movable with respect to said case and each having one end projecting so as to cover one of the holes in said case and the other end of each plate projecting through said slot; a slide movable at

30 the side of said slot and engaging the ends of 45 the plates in said slot, and registering devices coacting with said rods.

35. In a voting-machine the combination with a case, of a plurality of rods in said case; registering devices coacting with said rods; 50 plates projecting over and covering the operating ends of a limited number of said rods; cams at the other end of said rods, and means whereby the rotation of said rods to register a vote will simultaneously move 55 them by means of the cams in a lengthwise direction to project the operating ends between said plates.

40. In a voting-machine the combination with a case, of a plurality of rods in said case; 60 registering devices coacting with said rods; plates projecting over and covering the operating ends of a limited number of said rods; cams at the other end of said rods; pins on said rods and projecting over said cams, and 65 stop-plates adjacent said rods to limit the rotation of the latter and to maintain the rods in the positions the cams cause them to assume when rotated.

45. In a voting-machine the combination with a case, of a plurality of rods in said case; 70 registering devices coacting with said rods; plates to cover the operating ends of a limited number of said rods; a cam at the other end of each of said rods; a pin on each rod 75 and projecting over the surface of the adjacent cam; a stop-plate adjacent each cam and arranged to receive the pin and support the rod when the latter is rotated and moved lengthwise to project its operating end between 80 said plates, and means for moving said stop-plates and retracting said rods.

50. In testimony whereof I affix my signature in presence of two witnesses.

WILLIAM J. WILKINSON.
